United States Patent Office

Des. 179,871
Patented Mar. 12, 1957

179,871

LIQUOR CABINET OR SIMILAR ARTICLE

Paul Wrablica, Jr., Corona, N. Y.

Application January 3, 1956, Serial No. 39,552

Term of patent 14 years

(Cl. D33—19)

Fig. 1

Fig. 2

Fig. 1 is a front perspective view of a liquor cabinet or similar article showing my new design.

Fig. 2 is a perspective view with the door portion in open position.

The rear of the cabinet is plain.

I claim:

The ornamental design for a liquor cabinet or similar article, substantially as shown and described.
